FIG. 1

FIG. 2

FIG. 3

FIG. 1 is a front view of my combined dial and hands for a clock or similar article embodying my new design; FIG. 2 is a side elevational view thereof; and FIG. 3 is a rear view thereof.

My combined dial and hands for a clock or similar article is characterized by the hands which are so formed that in certain positions in their travel around the dial they form a cross.

I claim:

The ornamental design for a combined dial and hands for a clock or similar article, substantially as shown and described.
